UNITED STATES PATENT OFFICE.

CHARLES F. MORGAN, OF JACKSON, TENNESSEE.

GRAIN DOOR.

Application filed January 19, 1926. Serial No. 82,347.

This invention relates to a grain door for box cars and seeks, among other objects, to provide a door which will not only prevent the loss of grain from the car but will also exclude rain, snow, wind, cinders, and sparks, and will thus protect the contents of the car.

The invention seeks, as a further object, to provide a door embodying a pair of 15 swingingly mounted upper and lower sections, and wherein the upper section may be opened without disturbing the lower section.

A further object of the invention is to 15 provide a door wherein the upper section may, if necessary, be removed without entering the car.

Still another object is to provide a door wherein, when the door is closed, the securing means therefor may be sealed to thus provide a safeguard auxiliary to the usual seal, for protecting the contents of the car against theft.

And the invention seeks, as a still further 25 object, to provide a door which may be readily installed and which, when not in use, will not be in the way.

Other objects of the invention not specifically mentioned in the foregoing will appear during the course of the following description.

In the accompanying drawings:

Figure 1 is an elevation showing a conventional box car equipped with my improved grain door.

Figure 2 is an elevation looking at the inner side of the grain door, the floor and roof of the box car being shown in section.

Figure 3 is a horizontal sectional view 40 on the line 3-3 of Figure 2, looking in the direction indicated by the arrows.

Figure 4 is a vertical sectional view on the line 4-4 of Figure 1, looking in the direction indicated by the arrows, this view 45 showing, in dotted lines, the upper section of the door swung up in open position.

Figure 5 is a detail perspective view showing one of the socket members and one of the locking plates for the locking bolts of 50 the door.

Figure 6 is a detail perspective view looking at one of the upper corners of the upper section of the door.

Figure 7 is an elevation looking at the 55 inner side of a slightly modified form of

grain door, the door being shown applied to a conventional box car and the floor and roof of the car being shown in section.

Figure 8 is a vertical sectional view on the line 8-8 of Figure 7, looking in the direction indicated by the arrows.

Referring now more particularly to the drawings, I have illustrated my improved grain door in connection with a conventional box car, one side wall of which is indicated at 10, while the floor and roof of the car are indicated at 11 and 12 respectively. Secured on the outside of the side wall 10 above and below the usual door opening therein are tracks 13 and slidably supported by said tracks is the customary outer door 14. The door is equipped with a member 15 to cooperate with a plate or like device 16 on the car for securing the door closed and, as will be observed, the member 15 is apertured to receive a conventional seal so that the door may be sealed in closed position, as will be well understood.

Coming now more particularly to the subject of the present invention, I preferably form the improved grain door of a relatively wide lower section 17 and a correspondingly narrow upper section 18. As brought out in Figure 4, the lower section 85 is preferably formed of a plurality of horizontally disposed planks arranged one upon the other, edge to edge, and overlying the end edges of said planks, as best shown in Figure 2, are metallic end cleats 19, screwed 90 or otherwise secured to said planks for rigidly securing the planks together. Extending through the side wall 10 of the car and through the door section 17 near a lower corner thereof, as seen in Figure 2, is a 95 bolt 20 pivotally mounting said section so that the section may, as shown in dotted lines in Figure 2, be swung up from across the door opening to lie against the wall 10 of the car at its inner side, and extending 100 between the floor 11 and roof 12 of the car is a plurality of retaining bars 21 disposed to extend in front of the opened door section, for maintaining said section closely against the side wall of the car. Fixed to 105 the inside of the wall 10 at the side of the door opening remote from the pivot is a keeper plate 22 for holding the free end of the door section tightly closed. This plate 110 is substantially Z-shaped in cross section,

and, as will be observed, one flange thereof is secured to the wall 10 of the car while the oppositely directed flange of the plate is disposed to engage over the free end of the door section for binding said section against the inner face of said wall.

The upper section 18 of the door, like the lower section 17, is preferably formed of a plurality of horizontally disposed planks laid edge to edge upon each other and overlying the end edges of said planks, as seen in Figure 6, are metallic end cleats 23, screwed or otherwise secured to said planks for rigidly securing the planks together. The door section 18 is further equipped at its inner side with transverse reinforcing cleats 24 located at the ends of said section, and extending longitudinally of the section at its lower margin is a bottom cleat 25 disposed to overlap the upper margin of the lower door section 17.

Suitably fixed to the roof 12 of the car are spaced hinge loops 26, and suitably fixed to the door section 18 near the ends thereof are hinge plates 27, each provided at its upper end, as shown in Figure 6, with aligned hinge loops 28 disposed to straddle one of the loops 26. Extending through said loops are hinge pins 29 pivotally mounting the door section to swing inwardly and upwardly toward the roof of the car, as shown by dotted lines in Figure 4, to open position. Fixed to the outer side of the door section 18, at its lower margin, is a medially disposed eye plate 30, and fixed to the roof 12 of the car is a hasp 31 disposed to engage over the eye of said plate so that, as will be seen, the door section 18 may be readily secured in elevated open position. Formed in the door section, near the ends thereof, are hand openings 32, and normally closing said openings are hinged cover plates 33 overlying the openings at the inner side of the door section.

Countersunk in the vertical margins of the door casing, as particularly seen in Figure 3, are horizontally aligned socket members 34 one of which is shown in detail in Figure 5 of the drawings, and fixed to the ends of the door section 18 near the lower margin thereof, are angle shaped locking plates 35, the outstanding lugs of which are provided with apertures 36 disposed in horizontal registration with the socket members 34. Hingedly mounted upon the inner ends of the plates 35 are stop members 37, and extending freely through the openings 36 of said plates are eye bolts 38 screwed into the socket members 34. Thus, the bolts 38 will secure the door section 18 tightly closed and since the cleat 25 of this section overlies the upper margin of the door section 17, this latter section will also be held tightly closed so that the grain cannot escape from the car, while wind, snow,

rain, cinders, or the like, will be excluded. After the bolts 38 have been arranged in position, the stop members 37 are then swung up, when the wires of ordinary seals, as conventionally shown at 39 in Figure 1, 70 may be passed through the eyes of said bolts and through said stop members, for sealing the door. As will be perceived, the bolts 38 cannot be removed until the stop members 37 are swung down to lie against the outer face of the door section 18 and since said stop members cannot be thus swung to inactive position without breaking the seals, the unauthorized removal of the bolts will be made known. 80

To gain entrance to the car, when the car is loaded, the bolts 38 are first removed, and then the door section 18 is swung up and secured by the hasp 31. Should the grain be piled against the door section 18 so as to 85 make it impossible to thus swing said section upwardly, a hand is inserted first through one and then through the other of the hand openings 32 and the hinge pins 29 removed. The upper section 18 of the door will thus be 90 freed so that said door section may be moved to one side. After the car is emptied, the door section 18, is, of course, again mounted in place by means of the hinge pins and secured, by means of the hasp 31, in elevated 95 open position, and the door section 17 may be swung to open position lying behind the retaining bars 28.

In Figures 7 and 8 of the drawings, I have 100 illustrated a slight modification of the invention wherein the lower section of the door is indicated at 40 and the upper section at 41. The lower section is constructed and mounted as in the prior embodiment of the invention and the upper section, while being 105 constructed as in the prior embodiment of the invention is, however, mounted to swing in a plane parallel with the side wall of the car. Countersunk in said side wall, as shown in Figure 8, is a socket member 42, and 110 screwed into said socket member is a pivot bolt 43 extending freely through the door section 41 near the adjacent upper corner thereof. Thus, the bolt 43 will support the door section 41 to swing downwardly to open position, and pivotally mounted upon the adjacent end of said door section is a hook 44 engageable with an eye 45, as shown in dotted lines in Figure 7, for securing the door section in open position. Preferably, 115 retaining bars 46, like the bars 21, are provided to extend in front of the door section in the open position thereof. Projecting from the side wall of the car above the door opening therein, is an eye 47, and pivoted upon the free end of the door section is a hook 48 engageable with said eye for securing the door section in closed position, the door section being provided with hand openings like the openings 32, so that the hook 120 125 130

48 may be readily reached and disengaged from said eye when it is desired to open the door. Normally closing the hand openings of the door section are cover plates 49 like the plates 33. Surrounding the pivot bolt 43 is a spring 50 pressing the door section 41 tightly against the side wall of the car and, as will be observed upon reference to Figure 8, the bolt 43 is elongated so that the door section may, after the hook 48 has been disengaged from the eye 47, be shifted along said bolt against the tension of the spring 50 out of register with the door section 40 so that the door section 41 may be swung downwardly to open position. Otherwise, this modified structure is identical with the preferred embodiment of the invention and further description is accordingly believed unnecessary.

Having thus described the invention, what I claim is:

A car door including in combination with a box car having a side wall provided with a door opening, mating door sections, means swingingly mounting one of said sections for movement to open position in a plane parallel to said side wall, means mounting the other of said sections to swing inwardly and upwardly to open position and including removable hinge pins, the latter section being provided with hand openings through which said hinge pins may be removed for detaching the latter section, and means for securing the sections in closed position overlying said opening.

In testimony whereof I affix my signature.

CHARLES F. MORGAN. [L.S.]
